Des. 180,891

Patented Sept. 3, 1957

180,891

COMBINED WATER CLOSET AND FLUSH TANK

Frank E. Cherry, Agate, Nebr.

Application March 29, 1956, Serial No. 40,827

Term of patent 14 years

(Cl. D4—5)

Fig. 1.

Fig. 2.

Fig. 3.

*Fig. 4.**Fig. 5.**Fig. 6.*Figure 1 is a perspective view of a combined water closet and flush tank with the lid in closed position, showing my new design;

Figure 2 is a perspective view thereof with the lid in a closed position and as seen from the opposite side;

Figure 3 is a front elevation thereof as viewed in Figure 1;

Figure 4 is a perspective view thereof showing the lid and seat portions in raised position;

Figure 5 is a side elevation thereof showing only the lid in raised position; and

Figure 6 is a rear elevational view thereof as seen in Figure 1.

The essential features of the design reside in the portions shown in full lines.

I claim:

The ornamental design for a combined water closet and flush tank, substantially as shown and described.
